UNITED STATES PATENT OFFICE.

EMIL EINFELDT, OF DAVENPORT, IOWA, ASSIGNOR TO BETTENDORF METAL WHEEL COMPANY, A CORPORATION OF IOWA.

AXLE.

No. 815,582.

Specification of Letters Patent.

Patented March 20, 1906.

Application filed September 9, 1905. Serial No. 277,787.

To all whom it may concern:

Be it known that I, EMIL EINFELDT, of Davenport, county of Scott, and State of Iowa, have invented a new and useful Improvement in Axles, of which the following is a specification.

This invention relates to axles, and has reference more particularly to the wheel-carrying spindles, the invention being peculiarly applicable to that form of spindle constructed from a flanged bar, in which the flanges are rounded to present curved bearing-surfaces, leaving longitudinal spaces between the inner faces of the rounded flanges and the body of the spindle. In certain types of spindles of this form the rounded bearing-surfaces formed conjointly by the flanges are not continuous, being interrupted where the edges of the flanges terminate, and it has been the practice in order to afford a continuous uniform bearing for the wheel-hub to apply to the spindle a bearing or wear collar. This practice, however, is objectionable for many reasons, mainly on account of the expense involved.

My invention is designed to avoid this objection; and it consists in applying in the longitudinal spaces between the rounded flanges and the body of the spindle filling blocks or members shaped exteriorly to conform to the general rounded curvature of the flanges, so that a continuous uniform cylindrical bearing-surface is presented, to which the wheel may be directly applied without the intervention of a bearing-collar.

I prefer to form the filling-blocks of wood or other fibrous material in order to adapt them to retain the lubricant to a proper degree and to distribute the same effectively to the bearing-surfaces.

The invention consists also in the details of construction and combination of parts hereinafter described and claimed.

In the accompanying drawings, Figure 1 is a longitudinal sectional elevation of one end of an axle and its bearing-spindle having my invention embodied therein and showing the wheel-hub applied thereto. Fig. 2 is a vertical transverse section on the line *a a* of the preceding figure. Fig. 3 is a similar view on the line *b b*. Fig. 4 is a similar view on the line *c c*. Fig. 5 is a transverse section show-

ing my invention embodied in a spindle of slightly different form.

Referring to the drawings, 1 represents the body of an axle, 2 the wheel-spindle, and 3 the wheel-hub mounted thereon. In the present instance the axle consists of a flanged bar of I form in cross-section, the spindle being integral therewith and formed by rounding the flanges at the end of the bar, producing an upper curved bearing-surface 4, formed by the upper flanges, and a lower curved bearing-surface 5, formed by the lower flanges, which bearing-surfaces are interrupted where the edges of the flanges terminate, this construction leaving longitudinal spaces 6 and 7 between the inner faces of the rounded flanges and the body of the spindle, in the present instance the central connecting-web 8. In applying my invention to a spindle of this form I insert in each of these longitudinal spaces a longitudinal filling block or member 9, of wood or other fibrous material and of a cross-sectional form, which will snugly and tightly fit said spaces, the filling-block having an inner flat side 9^a, which bears along the side of the web 8; upper and lower curved surfaces 9^b, which bear at the inner faces of the upper and lower flanges; outwardly-extending upper and lower shoulders 9^c, which extend along the edges of the flanges, and an outer curved side 9^d, forming a continuation of the upper and lower bearing-surface 4 and 5 of the spindle. It is seen, therefore, that in conjunction with the upper and lower bearing-surfaces of the spindle these filling-blocks form a truly circular and continuous surface for the spindle to which the wheel is directly applied, as shown in Fig. 1, without the necessity of providing an intermediate bearing-collar.

At their inner ends the filling-blocks extend beyond the spindle and for a short distance along the web of the axle, to which web they are fastened by a bolt 10, extending through said parts. At their outer ends the filling-blocks terminate a short distance inward of the extremity of the spindle, to which is applied a cap 11, formed interiorly to snugly fit the upper and lower bearing-surfaces 4 and 5, which cap is provided on its interior with ribs 11^a, Fig. 3, extending inward and fitting between the edges of the

curved flanges of the spindle. This cap is held in place by a bolt 12, extending through the ribs and the web of the spindle and confined by the cotter-pin 13.

- 5 It will be observed that the access of dust or sand to the bearing-surfaces is effectually prevented at the inner end of the spindle by the filling-blocks and at the outer end by the cap 11, the inner end of which extends beneath the outer end of the hub, thus forming an effectual seal. From the continued application of the lubricant the fibrous filling-blocks become saturated with the same, and by contact directly with the hub-bearing surface it is evenly and uniformly distributed in the proper quantities for effective lubrication.

If desired, a longitudinal groove 9^e may be formed in the outer curved side of the filling-block to form a reservoir for the lubricant.

While I have shown my invention applied to a spindle formed from a bar of I form in cross-section, it is manifest that the invention is applicable as well to spindles formed from bars of other cross-sectional forms—such, for instance, as a bar of Z form, as shown in Fig. 5, comprising a central connecting-web and two oppositely-extending angularly-disposed flanges. It is obvious also that the invention is applicable to spindles formed from a flanged structure built up of laminae of metal sheets.

Having thus described my invention, what I claim is—

- 35 1. In combination with a metallic bearing-spindle comprising a web and integral rounded flanges with longitudinal spaces between the flanges and the web, independent filling-blocks of fibrous material extending, one at 40 each side of the web in the longitudinal space between the flanges and the web, said blocks having their outer surfaces formed to constitute a continuation of the bearing-surface of the flanges, and means for maintaining 45 said blocks fixedly in place.

2. In combination with a metallic axle-body comprising a web and integral longitudinal flanges, a wheel-bearing spindle forming an integral continuation of the body, and 50 comprising a web and curved flanges constituting the wheel supporting and bearing surface, and independent filling-blocks of wood, seated on opposite sides of the web respectively, in the longitudinal space between the 55 flanges and web, said blocks having their outer surface curved to form a continuation of the bearing-surface of the flanges, and a

fastening device securing the inner ends of the filling-blocks fixedly to the web of the body portion.

3. In combination with a metallic axle-body of I form in cross-section, an integral bearing-spindle comprising oppositely-disposed curved flanges constituting the bearing-surface of the spindle, and a central web connecting said flanges, filling-blocks of fibrous material seated in the longitudinal spaces at the opposite sides of the web, and having their inner ends terminating beyond the inner ends of the spindle, said filling-blocks having an inner flat side bearing against the side of the web, upper and lower curved surfaces bearing against the inner faces of the flanges, and outer curved sides forming a continuation of the bearing-surface of the flanges, and a fastening device securing the inner end of the blocks firmly to the web of the axle-body.

4. In combination with a metallic axle-spindle comprising rounded flanges and a connecting-web with longitudinal spaces between the inner faces of said flanges and the web, independent fibrous filling-blocks extending in said spaces and having their outer sides formed exteriorly to constitute continuations of the bearing-surface of the flanges, and means for securing said blocks fixedly in place.

5. In combination with an axle-spindle comprising rounded flanges, with a space between the edges of the flanges, a wheel mounted on the spindle, a confining-cap applied to the end of the spindle and formed with an inwardly-extending shoulder fitting between the edges of the flanges, and a fastening device securing the cap to the spindle.

6. In combination with an axle-spindle comprising rounded flanges oppositely disposed, with spaces on opposite sides of the spindle, between the edges of the flanges, a wheel applied to said spindle, a confining-cap on the end of the spindle, shoulders on the inner surface of the cap at opposite sides, extending between the edges of the flanges, and a fastening-pin extending through the cap-shoulders and spindle, and serving to fasten the cap on the spindle.

In testimony whereof I hereunto set my hand, this 22d day of August, 1905, in the presence of two attesting witnesses.

EMIL EINFELDT.
